UNITED STATES PATENT OFFICE.

WILLIAM F. GOULD, OF DES MOINES, IOWA.

RAILWAY-RAIL SPLICE.

SPECIFICATION forming part of Letters Patent No. 466,408, dated January 5, 1892.

Application filed June 4, 1885. Serial No. 167,667. (No model.)

To all whom it may concern:

Be it known that I, WILLIAM F. GOULD, of Des Moines, in the county of Polk and State of Iowa, have invented an Improved Railway-
5 Rail Splice, Angle-Bar, Fish-Plate, and Shim Joint or Splice, of which the following is a specification.

My object is to facilitate forming a rail-joint or splicing a broken rail at any time or
10 place; to give each end of each rail the proper support at the proper place on the rail; to relieve the undue vertical strain on the rails, chairs, angle-bars, or fish-plates at the joint caused by the wave motion of the rails while
15 under the immediate passage of trains or engines; to provide for and to take up the wear caused by long usage of the rails or their connections at the point where this wear takes place; to provide an opening in the splice or
20 to arrange the chairs so that while they are in position sand, gravel, or any substance liable to accumulate in them can escape while the ends of the rails are apart, as required to prevent such foreign substances from causing
25 damage to the joint; also, to properly take care of expansion and contraction by so arranging the rails and their fastenings at the joints that the joints will be each equally open in cold weather or when the
30 rails are contracted, and also to provide for and prevent the creeping of tracks when placed in a railway-track and operated as such.

My invention consists of a chair *b*, angle-bar *k*, or combination of chairs or angle-bars to form a rail-joint, and to provide for the wear of the same after it has taken place merely by tightening up the bolts.

Figures 1, 4, and 5 are transverse sections
40 of my improved chair and joint. Figs. 2 and 3 are side views of my complete joint. Figs. 6, 7, and 8 are perspective views of my chairs and angle-bar, while Figs. 9 and 10 are views of my clamping bolt and jaw to produce parallel jaws in a rail joint or splice.

Jointly considered these figures clearly illustrate the construction and combination of the different elements and the novelty and utility of my complete invention.

50 *a* is the horizontal portion of my chair, adapted to rest upon one or more parallel cross-ties.

b is the vertical portion of the chair, while *c* and *c'* are swells or raised portions of my chair, angle-bar, or fish-plate, adapted to engage the under side of the ball or T-head of the rail at the joint near the end of the rail, while *b'*, the inward projecting part of the vertical portion of the chair *b*, engages a portion of the top of the flange of the rail, as clearly shown in Figs. 1, 4, and 5.

Reference being had to my accompanying drawings, in Figs. 1, 4, and 5 the overlapping portions *b* of the chair touch the top part of the flange of the rail only partially, 65 while the top part of the vertical portion *b* touches the top of the web on the same side of the rail, so that when the bolts *o'* are tightened only the lower parts of the chair or angle-bar are moved toward each other, 70 as the top of the web of the rails prevents the tops of the chairs *b* from being drawn together. Therefore it is seen that the chairs have a slight rotary movement, and as the chairs are thus arranged it brings unworn 75 surfaces in contact. Relative to the chairs and rails, the openings caused by wear are reduced whenever the nuts are tightened on the bolts *o'* or clamping bolts *g h i*, as clearly shown in Figs. 1, 4, and 5. 80

I am aware that bearing-surfaces at the top of a chair or angle-bar have been made to engage the web of a rail; but my manner of forming a bar adapted to be adjustably combined with a rail to engage the under side of 85 the ball of the rail, and also the top portion of the flange of the rail for the purposes stated, is novel and advantageous in making and maintaining a rail-joint efficient and safe. 90

Figs. 6 and 7 in my accompanying drawings are views of my chairs *b*, formed of metal by means of rollers, dies, or cast in a mold. *a* is the base, *b* is the vertical portion, and *b'* the portion adapted to overlap and 95 touch the part of only a portion of one side of the flange of a rail.

d in Figs. 1, 3, 4, 5, and 8 is an aperture in the base *a* of the chair near its central part, arranged to come under the abutting ends of 100 the rails, so that sand or dirt of any kind dropping between the ends of the rails can pass through and out of the chair.

In Figs. 1 and 5 the complete chair *b* is

made in halves, with an aperture d extending the entire length of the chair, and each side or half is adapted to be placed laterally under each side of the rails at the joint or 5 for the purpose of splicing a broken rail, and longitudinal movement of the rails relative to the chair can be prevented by putting bolts or stops through the corresponding holes o in the rails and chairs, and vertical 10 wear be taken up by operating the nuts.

In Figs. 3 and 4 the chair b is complete in one piece and engages the under side of the 15 balls of the rail on one side. The overlapping portion b engages a portion of the flange on the same side of the rail, while the horizontal portion a extends under the base of the rail and engages the lower part of the angle-bar k on the opposite side of the rail at the joint, and the complete joint is made 20 by means of two bolts o' , put through one rail, and with my clamping-bolt $g\ h\ i$ and jaw n I then secure the other rail on the chair by 25 means of spikes passed through the chair, clearly showing how one end of the rail is bolted to the ties, while the other end has longitudinal movement, by which means I prevent creeping of track and equalize the 30 openings at each joint caused by heat or cold expanding or contracting the rails, as clearly shown in Figs. 3 and 4.

In Fig. 1 the holes o in the rail and chair are larger than the bolts, made so in order 35 that the chair can assume different angles to the web or base of the rail without cramping the bolts and also allow the rails to expand and contract during hot or cold weather. The joint in Fig. 1 is also made by bolts being put through the corresponding holes in each end of each rail and each side of the chairs at the 40 joint. Nuts are then placed upon the screw-threaded ends of the bolts o' and then tightened up, which draws the chairs toward each other while taking up wear.

In Fig. 5 of my accompanying drawings is a 45 sectional view of my complete chair, jaw n and clamping-bolt $g\ h\ i$ arranged and combined to form a splice or joint; and in Fig. 2 the joint or splice is shown resting upon three ties and formed by means of my chairs b being placed under the abutting ends of two rails and on the top surface of three ties, and also by passing the screw-threaded end of my 50 clamping-bolt $g\ h\ i$ across under the chairs and through the hole x in my jaw n , while the neck h fits into a notch a' of the chair and the head i on top of the chair. Then by 55 drawing each half of the complete chair together I complete the joint or splice, and to fasten the thus-completed joint to the ties I 60 drive spikes through perforations or notches a' in the horizontal portion of the chair, as shown in Figs. 1, 2, and 3.

I am aware that chairs have been formed 65 in halves or in one piece and made to fit the contour of the rails closely at the joint; but with such devices it would be impossible to provide for or take up the wear that occurs

in railway-chairs or splices by long use, for the reason that as the inside of the vertical portions of such splices fit the web of the 70 rails closely they could not be drawn toward each other and in bisected chairs made to fit the rails and their bases to come together. When in proper position, they cannot be arranged to take up any wear or lost motion 75 that takes place between the rails and chairs after they have been in use, because their under sides or horizontal portions come together. It is also impossible for any sand or other substance to get out of the chair so 80 made that drops into it from the sand-box of an engine or dirt from the train, which would grind or wear the rail and chair if left in it; but my chair b , as shown in Figs. 1, 5, and 7, does not fit the contour of the rail closely, 85 but engages the ball and flange of the rail firmly, and has an aperture d extending the entire length of the complete chair.

Figs. 4 and 7 show the complete chair b in one piece, while in Figs. 1, 3, 5, and 6 are 90 shown modified forms of the chair b , and they can only be used by combining two of them together with the rails to form a complete rail-joint.

I am aware that chairs, angle-bars, and 95 fish-plates have been formed with their top surfaces and bearings parallel to those surfaces which engage the top portion of the flanges of the rail at the joints, or with the upper and lower edges of their vertical portions parallel to each other, so that they engage 100 the balls, webs, and flanges of the rails at the joints, or with the upper and lower edges of their vertical portions parallel to each other, and that they engage the rails 105 the entire length of the chairs, bars, or plates, and as the wear in a rail-joint takes place first at the extreme end of the rail, which is at the center of the angle-bar, chair, or fish-plate, and works back toward the center of 110 the rail, and as the under side of the T-head of the rail is wedge-shaped, and the flange also, it would be impossible to take up the wear that always occurs at that particular point on the rail and splice bars by 115 long use with such a chair or splice as above described. To overcome this I make a chair, angle-bar, or fish-plate with their top edges or top-bearing surfaces raised at their centers higher than at each end of the same 120 bearing-surfaces, so that when the wear occurs it or the lost motion can be reduced by operating the nuts on the bolts o' , and the chairs so made and so placed will act as an 125 equalizer to the weight on the rails at the joint, relative to the ties and rails, for the reason that the raised bearing-surfaces c' only engage the under side of the balls of the rails, and as the base a of the chair b is plain and not re-enforced, and the aperture d extends 130 the entire length of the chair in that form shown in Figs. 1, 5, and 6, when in position it will be seen that the base of the chair will yield at its ends only when the weight of

passing wheels is at *l* or *p* on the rail over it, because the vertical portion of the chair does not touch the ball of the rail at the end of the chair. Consequently the weight on the rails is thus thrown on the center of the chair at *c'*, where it is re-enforced, which it is intended should be done by my rail-splices, because the center of a rail-splice is the proper place to support the end of a rail. Therefore the splice herein described is so formed as to allow the rail vertical and horizontal movement relative to the splice at each end of the same and yet hold the ends of the rails rigid at the center of the splice, as clearly shown by *c'* in Figs. 1, 2, 3, 4, 5, 6, 7, and 8.

In Fig. 8 is shown my angle-bar *k* with a raised portion *c'* on its bearing-surface, and when in position on the rail and bolted to each end of each rail the ends of the rails rest upon the raised portions only of the bars or plates, thereby allowing the wear on them to be properly taken care of, and they will also act as an equalizer to the joint relative to the ties and rails while under the weight of passing wheels.

Figs. 2 and 3 of my accompanying drawings show side views of my improved joint. Fig. 2 shows a joint on three and Fig. 3 a joint on two ties made with my improved chairs and angle-bar.

As before stated, I provide for the relief of vertical strains at the joint by a peculiarly-formed chair-splice, bar, or fish-plate made in such a manner that its center is higher than its ends, so that it engages the ends of the rails at the joint, and yet allows the wave motion of the rail to continue until the wheels of moving engines or trains pass over the extreme end of the rail.

By referring to Figs. 2 and 3 it will be seen that when the wheels of an engine or train are one at *p* and the other at *l* there is an upward or cantilever strain at the joint or extreme end of the rails, and should the chair, angle-bar, or rail-splice fill the rail between its ball and flange closely the entire length of the splice or at the extreme ends of the same splice the vertical strain at the center of the chair, bar, or splice would be to tear its top edge open vertically. To overcome this and to relieve such strains on the rails and their splices, I change the point of leverage by raising the center of the splice higher than its ends, thereby allowing the rails at each end of the splice to have undulating, vertical, or wave movements relative to the splice as the wheels pass over the joint; and I accomplish this by making the chairs, bars, or splices with their top edges higher in the center than at their ends, as before described.

In Figs. 1 and 5 the joint is formed by means of my bisected chair *b*, and it is clearly shown that I do not contemplate the halves of the chair *b* fitting the rails perfectly or allowing their horizontal portions *a* to come together under the rails. I so construct the chair that the raised portion *c'* engages the

under side of the balls of the rails, while *b'* engages the top of a part of the flanges and on the same side of the rails. *d* is the aperture formed by the splices not coming together, as shown in Figs. 1 and 5.

Fig. 9 is a perspective view of my clamping-jaw *n*, adapted to extend partially under the horizontal portion *a* of the chair *b*, adapted in form on its rear to engage the outside surface of a portion of the chair. A bolt-hole *x* through its base adapts it to be combined with my screw-threaded clamping-bolt *g h i* by passing the screw-threaded end of the bolt *g* through it and then placing a nut on the screw-threaded end, as clearly shown in Figs. 2, 3, 4, and 5.

h in Figs. 2, 3, 4, 5, and 10 is adapted to fit into the notch *a'* of the chair to prevent longitudinal movement of the clamping device relative to the chair, while *i*, the head of the bolt, rests upon the outside edge of the chair and prevents the bolt from being pulled out of the chair when the nut is being drawn, with the jaw *n* on one side of the chair and the clamping-bolt attached in the manner described to a chair on the opposite side of the rail, as clearly shown in Figs. 2, 3, 4, and 5, and the nut on the bolt *g* tightened, so that the chairs will be drawn toward each other and the joint secured.

For the purpose of forming a rail-joint I place the chair upon one or more cross-ties and slip the horizontal portion *a* of each chair under the abutting ends of two rails, one-half of the chair on each side, in such a manner that the center of the raised portion *c* of my chair will come under the abutting bearing-surfaces at the ends of the rails, and the top part *c'* of my chair will engage the under side of the T-head or ball of the rail, while *b'* will engage the top of the flange, and then the bolts *o* are put through the holes *o* in the chair *b* and nuts placed upon their screw-threaded ends, and as the nuts are drawn the halves of the chair will slip upon the flanges of the rails and toward each other and in turn force upward the vertical portions *b* of the chair or splice and cause the swell *c* or raised portion *c'* to firmly engage the under side of the balls or T-heads of the rails and complete the joint or reduce vertical wear.

Having thus described my invention and to make it more clear, if possible, I will say that I wish to cause the chairs or splices, when combined with the rails and ties, to form an equalizing-joint, so that when the wheels are passing over the joint the rails and ties at each end of the chairs or angle-bars can conform to the weight upon them, and when the wheel of a car or engine is passing between and over the extreme end of the rail each end of the angle-bar, chair, or splice will sustain that weight equally alike, even though one of the ties be lower than the other at the joint on either end of the chairs or angle-bars.

Conceding that it is not new to form a chair

in two parts and clamping the parts to the abutting ends of two rails; that it is not new to form or to provide a perforation for the escape of sand through the chair from between the ends of the rails, and that the top edge of a plate clamped to the webs of the rails has had vertical projections that came in contact with the balls of the rails, it is nevertheless believed to be novel to form a chair in two parts that will not fit closely to the flanges and webs of the rails, but come in contact with those parts of the rails at three distinct points and engage the balls of the rails at the central portions of their top surfaces only, as shown and described, and in such a manner that the two parts of the chair can be adjusted vertically and horizontally relative to the ends of the rails by means of bolts for the purpose of compensating for wear and maintaining a firm joint where the track is straight or curved.

I am aware that a chair has been formed in three pieces hinged together in such a manner that the top portions of the hinged sections could be adjusted horizontally by means of screw-bolts and their top edges drawn toward the webs of the rails to compensate for wear; but my manner of forming a chair in two pieces and drawing them together at the base to cause the elbows of the vertical portions to slide inward and upward on the unworn parts of the flanges of the rails to elevate their top edges relative to the balls of the rails to compensate for wear without moving the top portion horizontally relative to the webs of the rails is new and advantageous in maintaining a firm joint.

One of the objects of the invention, as hereinbefore described, is to properly take care of the vertical wear which takes place under the ball of a rail and on top bearing-surface of a rail-splice.

What is meant in this specification by the words "top bearing-surface" is that surface of the angle-bars or rail-splices which comes in contact with the under side of the balls of the rails in a rail-joint. This wear makes a peculiar form, as it occurs only at one place on the top bearing-surface of the splices, which is at the extreme ends of the rails, and as the wear continues it extends its action backward each way toward the ends of the angle-bars or splices, so that after the angle-bars or rail-splice have been in position some time or have been under constant use their top bearing will be worn concave at their centers and the under side of the balls of the rails will be worn also at their ends. Therefore, if the angle-bars or rail-splices fit the contour of the rails closely, the entire length of the splice before it is worn it cannot be adjusted to fit the worn portion against the rails, for the reason that the unworn portions of the splices do not admit of their positions being changed relative to their vertical adjustment after such wear has taken place, because they fit closely when they are not worn.

I am aware that prior to my invention rail-splices have been formed with their outside portions higher than the balls of the rails and adapted to engage passing wheels of engines or cars; but such devices are inoperative, for the reason that worn wheels would knock them loose and the intermediate portions of such splices were closely fitted to the contour of the rails the entire length of the splice. Therefore such said splices or angle-bars could not be adjusted to fit the rails after the splices were worn, and in such devices no provision whatever is made to take care of the wear which occurs between the splices and the rail at the particular points where such wear occurs. I overcome this difficulty by making the angle-bar or rail-splice slightly higher on the center of the top bearing-surface than it is at the ends of its vertical portion, which is done by means of a swell or slight re-enforcement *c'*, as shown in Figs. 2, 3, 4, 7, and 8, and I do not allow the angle-bar or rail-splice to fit the contour of the rail closely, thereby allowing for the vertical adjustment of the splice, and as the swell or re-enforcement on the central portion of the top bearing-surface is where the greater part of the wear comes it not only allows opportunity for the proper adjustment of the splice, but increases its usefulness, for the reason that it will last as long after the swell is worn off as an ordinary angle-bar or rail-splice, which is a new and advantageous result.

I am aware that rail-splices have been made thicker in the center than at their ends; but when such devices are placed in contact with the abutting ends of rails in a track the top bearing-surface of such devices wears the same the entire length of such top bearing-surface, and therefore is not adapted to perform the function intended by the inventor—viz., presenting the most bearing-surface where there is the most wear.

I am also aware that rail-splices have been made with the upper corners of their vertical sections rounded or circular in form, while the top and bottom bearing-surface of such devices were parallel the entire length of the said surface; but such devices cannot accomplish the object contemplated by my invention, for the reason that such devices fit the contour of the rail closely, and therefore cannot be adjusted to the rails after the vertical wear has taken place, as before described.

I claim as my invention—

1. A railway-chair consisting of the horizontal portion *a*, the vertical portion *b*, the inwardly-projecting portion *b'*, the top edge *c*, having a raised bearing-surface *c'*, adapted to engage the under sides of the ball of a rail and a part of the top of the flange of a rail, and with an aperture *d* in the base of the chair, as and for the purposes stated.

2. A railway-chair made in duplicate parts, adapted to engage the under side of the balls of the rails on each side thereof, a portion of the top of its flanges, and the base on each

side of the rail, and consisting of the horizontal portion *a*, vertical portion *b*, the inward-projecting parts *b'*, the top edge *c*, having a raised bearing-surface *c'*, with the aperture 5 *d o o*, arranged and combined with the bolts *o'*, and the abutting ends of rails in a railway-track, as illustrated in Fig. 1, substantially as shown and described.

3. A railway-chair consisting of the horizontal portion *a*, the vertical portion *b*, the inward-projecting portion *b'*, the top edge *c*, and top bearing-surface *c'*, as and for the purposes stated.

4. A railway-chair consisting of the horizontal portions *a*, the vertical portion *b*, the inward-projecting portion *b'*, the top bearing-surface *c'*, aperture *d*, and top edge *c*, as clearly shown in Figs. 3, 4, and 7, as and for the purposes stated.

5. The combination of a vertically and horizontally adjustable chair consisting of two mating parts with two rails and one or more cross-ties to produce a continuous aperture in the base of the chair and to operate, in the manner set forth in compensating for wear and in maintaining firm joints with even top surfaces in straight and curved track.

6. An angle-bar, fish-plate, or chair having a top edge *c*, a raised top bearing-surface *c'*, as shown and described, to operate in the manner set forth.

7. The combination of a vertically and horizontally adjusted chair having raised surfaces on its top edges, two rails, and two bolts passed through one of the rails only, as shown in Fig. 3, for the purposes stated.

8. A railway-chair, angle-bar, fish-plate, or splice-bar having a bearing-surface on its

top edge that is narrower at its ends than at its central portion and also lower at its ends 40 than its center for the purpose of supporting the abutting ends of two rails more rigidly at the longitudinal centers of the said bearing-surfaces than at the ends of the same bearing-surfaces, for the purposes stated. 45

9. In a rail-joint, an adjustable angle-bar or fish-plate so formed as to fit the under side of the ball of a rail and to come in contact with the top of the flange of a rail and with its top bearing-surface higher at its center 50 than at the ends of its top bearing-surface, substantially as set forth.

10. In a rail-joint, an angle-bar or rail-splice adapted in form to be vertically adjusted relative to a rail, so as to come in contact with 55 the balls and flanges of two abutting rails and having also a slight swell or reinforcement on and near the center of its top bearing-surface, substantially as set forth.

11. In a rail-joint, an angle-bar or rail-splice 60 adapted in form to be adjusted vertically and to come in contact with the balls and flanges of two abutting rails, also with having its top bearing-surface wider at its center than at its ends, substantially as set forth. 65

12. In a rail-joint, a vertically and laterally adjustable and interchangeable angle-bar or rail-splice adapted in form to be used on either side of a rail and having a boss on its top edge adapted to engage the under side of 70 the ball of the rail, substantially as set forth, for the purposes stated.

WILLIAM F. GOULD.
